UNITED STATES PATENT OFFICE.

ALBERT L. McDONALD, OF WOODLAWN, PENNSYLVANIA.

MINING TOOL.

1,427,609.

Specification of Letters Patent. Patented Aug. 29, 1922.

Application filed November 11, 1920. Serial No. 423,245.

To all whom it may concern:

Be it known that I, ALBERT L. McDONALD, a citizen of the United States, residing at Woodlawn, in the county of Allegheny and State of Pennsylvania, have invented certain new and useful Improvements in Mining Tools, of which the following is a specification.

My invention consists of an improvement 10 in mining tools, and particularly relates to a reamer for enlarging the inner end of a blasting hole.

In blasting coal or other minerals, a great advantage over the ordinary practice of exploding the charge in the end of a bore hole is secured by enlarging the inner end. This is especially true when the bore is enlarged by a lateral cavity extending all around the central bore and with a flat front wall on a 20 plane at right angles to the axial center of the bore. When so made, the explosive charge of powder, or the like, being confined between the rear end front walls of the enlarged cavity, surrounding the central 25 bore hole, will act with very great force against the front wall particularly, and will break the coal, etc. outwardly and laterally on diverging lines.

By such practice, the usual undercutting 30 of a vein is avoided, and blasting may be successfully and cheaply done by charges exploded in the rear of the middle part of the breast of the vein.

In carrying out my invention, I have produced a tool consisting of a cylindrical barrel capable of fitting somewhat loosely in a cylindrical bore hole having at its inner end an eccentrically mounted laterally extensible cutting tool capable of being gradually adjusted in and rotated by the barrel to 40 cut an enlarged cavity at the inner end of the bore hole having flat front and rear walls and of an area several times the cross sectional area of the bore hole, as hereinafter 45 described.

Referring to the drawings, showing one preferred form of the invention,

Fig. 1 is a view in side elevation, showing the tool in position at the termination of the 50 cut;

Fig. 2 is an enlarged view of the outer or handle end of the tool;

Fig. 3 is a longitudinal section, partly broken away, on the line III—III of Fig. 2;

55 Figs. 4, 5 and 6 are views of the inner end

of the tool showing successive positions of the cutter.

In the drawings, 2 is a cylindrical barrel of pipe form, of a length sufficient to extend inwardly of the length of an ordinary bore hole 3, with sufficient extension in front of it for easy manipulation, as in Fig. 1. At each end are bearing heads 4 and 5 respectively, fixedly secured to the barrel 2 by any suitable means, as welding or riveting. Inner head 5 is preferably provided with a clearance opening 7 for passage of cuttings outwardly and into the barrel.

At one side of the axial center, eccentric thereto, and as close to the wall of the barrel at one side as is practicable, is a cutter shaft 8 journalled in bearings 9 and 10 of heads 4 and 5, and provided at its inner end with the cutter arm 11 having the cutting terminal as shown. Arm 11 is secured by its hub to the squared or otherwise formed inner terminal 12 of shaft 8 and held thereon by a retaining nut 13 or the like. At its other end, shaft 8 is provided with a squared or otherwise formed terminal 14 so that it may be engaged by a wrench or other tool and adjusted to set the cutter 11 gradually outwardly through an enlarging annular path of cutting movement. A ratchet wheel 15 is secured to the shaft and is controlled by a spring-pressed pawl 16 mounted on head 4, so that the shaft may be gradually adjusted during the cutting operation and held in extended position. It may also be reversed to withdraw the cutter inwardly, as in Fig. 4, by retracting the pawl, or merely turned clear around to the position of Fig. 4. When it has been withdrawn and is in normal or retracted position, the cutter extends diametrically across the pipe, so that it may have a maximum length for a barrel of given diameter.

The outer end of the barrel 2 is provided with a turning crank handle 17 secured in any convenient way, as by a ring 18 embracing the end of the barrel and secured thereon, by a set screw 19 or otherwise.

The operation is as follows:

The hole 3 having been bored to the desired depth, the barrel 2 is inserted with the cutter 11 retracted, as in Fig. 4. Shaft 8 is then turned by its terminal 14, say one tooth of ratchet wheel 15, which brings the terminal of the cutter against the inner peripheral portion of the bore hole with suffi- 110

cient pressure. The entire barrel and cutter are then rotated by crank handle 17, the barrel being loosely journalled in the bore hole, until the cutter has made its initial 5 cut, and shaft 8 is then again adjusted for say one tooth of the ratchet wheel and the barrel again turned as before.

This operation is continued, the cutter 10 operating on an enlarging peripheral path as indicated at *a*, *b*, and finally resulting in the cavity *c*, Fig. 1, with the cutter extended to its limit. Pawl 16 may be then retracted and shaft 8 reversed, or may be more easily 15 continuously turned in the same direction, to close in the cutter, when the entire tool 20 may be withdrawn. Any cuttings which have passed through opening 7 and remain in the barrel may be easily discharged by dumping vertically through opening 7, as will be readily understood.

The cavity *c* may then be filled with the explosive charge, either fully or partially, and properly tamped and fired. The front 25 wall *d* being towards the direction of least resistance will receive substantially the full effect of the blast, its area being very largely greater than that of the central bore hole 3 with the result that the shot will force the 25 mass of mineral in front of wall *d* outwardly on the diverging lines of a conic section.

If it is desired to increase the depth of the cylindrical cavity *c* after the same is cut, the original cutter may be removed and another substituted of wider cutting face, within 30 any particular limits.

The tool is comparatively simple in construction, and is very durable and efficient in operation, and not liable to get out of order. It may be changed or varied in different details or otherwise by the skilled 40 mechanic to suit various conditions of use, but all such changes are to be considered as within the scope of the following claims.

What I claim is:

45 1. A mining tool consisting of a hollow cylindrical rotatable barrel provided with an eccentrically mounted laterally extensible cutter on one end thereof.

50 2. A mining tool consisting of a hollow cylindrical rotatable barrel provided with an eccentrically mounted laterally extensible

cutter normally extending across the inner end thereof, means for adjusting the cutter, and means for rotating the barrel.

3. A mining tool consisting of a cylindrical body portion having an eccentrically located cutter shaft provided at its inner end with a laterally adjustable cutter normally extending across the inner end of the barrel and an outer adjusting terminal, means for holding the cutter shaft and cutter in adjusted position, and means for rotating the cylindrical body portion.

4. In a mining tool, the combination of a tubular body portion having eccentrically located bearings at each end, a cutter shaft 65 extending therethrough, a laterally swinging cutter secured to the projecting inner end of said shaft outside of the barrel and across one end thereof, an adjusting terminal and ratchet mechanism at the outer end of said shaft, and a crank handle secured to the outer end of the tubular body portion.

5. A mining tool comprising a barrel provided with an eccentrically mounted laterally movable cutter, arranged to normally extend diametrically across the barrel.

6. A mining tool comprising a barrel provided with an eccentrically mounted movable cutter, arranged to be rotated relatively to the barrel, said cutter normally extending across the end of the barrel with its center of rotation and cutting portion substantially diametrically opposed, so that the cutter may be of maximum length.

7. A mining tool comprising a hollow cylindrical rotatable barrel, an apertured bearing member at one end of the barrel having an eccentric bearing therein, a bearing member at the other end of said barrel, a shaft 90 carried in said bearing members and having its inner end projecting beyond the inner end of said barrel, a cutter on said shaft, means for turning the barrel, means for turning the cutter to project it laterally, the opening in 95 said apertured bearing member being designed to provide for the passage of cuttings into the barrel.

In testimony whereof I hereunto affix my signature.

ALBERT L. McDONALD.
